UNITED STATES PATENT OFFICE

DAVID GRIMES, OF GRASMERE, NEW YORK, ASSIGNOR TO RADIO CORPORATION OF AMERICA, A CORPORATION OF DELAWARE

FILTER CIRCUIT FOR RADIO RECEIVING SETS

Application filed November 2, 1926. Serial No. 145,735.

My present invention has for its object to provide certain improvements in circuits for radio receivers which are primarily intended to afford substantially equal amplification of all the various wave lengths used in broadcast transmission and which will provide the necessary sharpness in tuning on each of said various wave lengths to enable them to be easily selected and the possibility of interference avoided. Stated in another way my invention contemplates a circuit, or combination of circuits, whereby equal efficiency throughout the broadcast band of radio frequencies is obtained, considered either from the standpoint of selectivity or amplification, in that in the arrangement proposed the tuning is equally sharp on the lower frequencies (which produce the long waves) and on the higher frequencies (which produce the so-called short waves), because I am able to prevent a falling off in the amplification of the longer waves which loss has been heretofore due to loss in the transference of energy of such longer waves in the usual induction

transformers. My invention broadly stated comprehends a method of effecting a circuit coupling between two or more audions or vacuum tubes connected in cascade which comprises selectively feeding back a portion of the amplified energy from the output of a second tube to the input of a preceding tube in amounts to substantially equalize the resultant amplification over a band of wave lengths.

To these and other ends, my invention further consists in certain additional improvements all as will be fully set forth in the accompanying specification and particularly pointed out in the claims appended thereto.

In the drawings,

Fig. 1 is a diagram showing in simplified form a schematic circuit illustrating one embodiment of my present invention;

Fig. 1^a is a diagram illustrating the relative directions in which the primary and secondary windings of the transformers are applied in practice.

Fig. 2 is a diagrammatic illustration showing one form of a commercial type of receiving circuit embodying my invention, and

Fig. 3 is a similar view illustrating the invention applied to the so-called inverse duplex receiving circuit.

Similar characters throughout the drawings illustrate similar parts.

My invention is directed particularly to providing a commercial type of circuit for radio receiving sets the success of which depends upon the satisfactory reception of radio signals on all of the various so called "broadcast" wave lengths which at the present time vary from 200 to 550 meters. The commercial success of such a set also depends upon the ability of the operator to effect selectivity between various stations operating under assigned wave lengths and to obtain a requisite and equal amplification of such wave lengths.

The outstanding point of criticism in many of the receiving sets in common use at the present time arises from the necessity of employing, when a plurality of audions or vacuum tube amplifiers are used, transformers comprising primary and secondary windings, and many inherent defects in such sets are attributable to the transformer action varying for different wave lengths. It is a well-known physical fact that on the shorter wave lengths, which are transmitted by the higher frequencies, the transfer of energy from the primary to the secondary coil of a transformer is much better than it is with the longer wave lengths which are transmitted by the lower frequencies. Conversely stated, when the circuits are tuned for the reception of the longer wave lengths there is a reduction in the amplification of the received signal. In attempts to obviate this difficulty certain circuit connections have been proposed, but in these arrangements the attempts to increase the amplification at the long waves have resulted in broadening the tuning, thus rendering the circuits as a whole less selective in the long wave lengths occupying the upper range of the broadcast band.

In the circuits disclosed in this application, I have, with full appreciation of the difficulties above outlined, selected a transformer most efficient at the shortest wave length to be received and combined with the circuits

associated therewith, means whereby, as these circuits are tuned in resonance with stations transmitting signals of varying wave lengths, the longer waves will be progressively and increasingly reinforced. For instance, assuming that a wave length of 250 meters shows a slight reduction in amplification, a small portion of the oscillations in step with this wave length emitted from the output circuit of the last amplifying tube is used by feeding it back to the input circuit of a preceding tube to bring the final amplification of this wave length up to the desired point, or that equal to the amplification obtained for a wave of 200 meters. Again, if the circuits are tuned for a wave length of, say, 300 meters, an increasing proportion of the corresponding wave length amplification or oscillation occurring in the output circuit of the last tube would be employed as the increment for bringing this wave length to a point of amplification equivalent to that of the 200 meter wave reception. At the extreme wave length used in broadcasting, or 550 meters, a considerably larger reinforcing current is thus utilized to compensate for the extensive reduction in the normal amplification which occurs at this frequency compared with the 200 meter efficiency.

This increased amplification obtained by reinforcement is equivalent to obtaining amplification by a reduced resistance. This increase in amplification it will be seen can therefore be obtained from a reinforcement of the circuit which becomes increasingly effective as the wave lengths are increased. This reinforcing of the original wave acts on the signal in the same manner as if the resistance in the circuit had been counterbalanced proportionately for each increase in wave length, thus maintaining the sharpness of the resonance curve substantially equal on all wave lengths.

In the simplified diagrammatic illustration shown in Fig. 1, the receiving circuit is composed of the thermionic amplifiers A and B, representing the first and second radio frequency stages, and a third tube C comprising the usual detector. The weak radio broadcast signals are received on the antenna 1 which is preferably connected with a tuned primary coil 2 from which a tap leads to ground. Associated with this coil is a secondary winding 3 located in the input of tube A by connecting one end to the grid 4 and its other extremity by a conductor 5 to the filament 6. Means are provided for tuning this circuit to the desired frequency of the incoming antenna wave by means of a variable condenser 7 bridged between the grid 4 and the conductor 5. The output circuit of the tube A consists of the plate 8, the primary winding 9 and the battery 10, the negative pole of which is connected to the filament 6.

The tubes A and B are coupled through a

transformer which also comprises the secondary winding 12, associated with the primary winding 9, and located in the input circuit of the second tube B comprising the grid 13 and filament 14. This circuit is tuned by the variable condenser 15 connected in bridge between said grid and filament. This input circuit, it will be understood, is tuned in resonance with the output circuit of the tube A. The output circuit of tube B comprises plate 16, primary winding 17, of the second radio frequency transformer, and the battery 18, the negative pole of which is connected to the filament 14. The secondary coil 19 of the last mentioned transformer is connected to the input circuit of the detector tube C which comprises the grid 20 and the filament 21. Tuning of this circuit is likewise accomplished by providing across the terminals of the last mentioned coil a variable condenser 22. If desired, the signal detecting device, such as a telephone receiver 23, can be connected directly in the output circuit of the tube C by connecting the plate 24 thereof with one side of the receiver circuit by means of the conductor 25 and completing the circuit from the receiver by another conductor leading to the battery 26, the negative pole of which is in turn connected by conductor 26^a to the filament 21. When a telephone receiver is employed in such an arrangement it is of high resistance and is bridged by a by-pass condenser 28 of small capacity.

The filament of the tube C is lighted by current from battery 29 and the filaments of tubes B and A are lighted by batteries 29^a and 29^b, the negative terminals of which are, for convenience in further description of the present circuit, illustrated as being grounded.

For the purpose of simplification I have shown in Fig. 1 a common lead 30 connecting the output circuit of the last radio frequency amplifier tube B with the input of the first tube A, and located therein, as indicated at 31, is a radio frequency filter coil of approximately .75 millihenries and 1000 ohms resistance. It will also be observed that in the output circuit of tube B between the negative pole of the battery 18 and the filament 14 I have placed a high resistance 32, of approximately 25,000 ohms, which affords a return from the battery 18 to the filament of tube B, this resistance being substantially equivalent to the internal resistance of the tube B itself.

Located in the input circuit of tube A between the filament 6 and the lead 30 there is a very much higher resistance 33 of approximately one megohm. The object of this resistance is to permit the grid 4 of tube A to be maintained at the same direct current potential as the negative end of filament 6 of tube A.

In conjunction with the aforementioned radio frequency filter coil 31, I place between its opposite ends and the lead connected to the negative end of filament 14 of tube B

filter condensers 34 and 35, the former having a capacity of .001 and the latter a capacity of .00025 microfarads. The condenser 34, which is the larger of the two capacities, is given such a value that it will pass 200 meter waves readily, the passage of the latter beyond this point being impeded if not completely restricted by the filter coil 31 the inductance value of which is such as to effectively stop the 200 meter wave. Any slight amount of electrical energy at this wave length which may leak through the filter coil 31 is finally passed back to the filament 14 of tube B through the filter condenser 35. This filter condenser 35 can be of smaller capacity than condenser 34 because only very slight portions, if any of the 200-meter currents will pass through the filter coil, and there is no tendency for such currents to pass beyond this point with the size mentioned of capacity 35 because this will effectively pass them to filament 14. This filter condenser 35 also functions as a return from the first tuned secondary coil 3 to the filament 6 of tube A, through the ground connections of batteries 29^a and 29^b.

The apparatus just described functions when the circuits described are tuned to the proper resonance for so-called long wave length reception in a slightly different manner from that previously described, in that the wave length energy encounters increasing difficulty in passing through condenser 34, finding at the same time a more ready path through the filter coil 31. These are well-known functions of condensers and coils in general, as a condenser offers more impedance to low frequencies than high frequencies and a coil performs in the reverse manner. The long wave currents passing with more ease through the filter coil 31 are forced on through the tuning coil 3 to grid 4 of tube A because of the high resistance 33 and the high reactance of condenser 35 at the long wave lengths. It can be seen therefore that a portion of the long waves which pass the filter coil 31 being of the same frequency as the incoming currents in the tuned circuit 3-7 reinforce the original, weak incoming current transmitted from the antenna to said grid 4. This reinforcing effect increases the original wave strength and counterbalances the effective resistance in the various tuning circuits so that not only an increased amplification is obtained but also sharper tuning is effected.

It can be seen from the action of the filter condensers 34-35 and coil 31 that the reinforcing becomes greater the longer the wave length and becomes less the shorter the wave length. The reinforcing therefore compensates for the decreased transfer efficiency between the transformer coils 9-12 which is well known to be less than half as effective at 550 meters as at 200 meters. The capaci-

tance, inductance and resistance in this filter combination may be varied from the values heretofore stated and it will be understood that the object is to so adjust them that the increase in reinforcing effect is proportional to the decrease in transfer effect between the transformer coils 9-12, thus giving an overall amplifying effect by a summation of the transferred energy plus the reinforced energy on every broadcast wave length.

In other words, the principle of the system herein described is to maintain what may be called constant and equal intensity value of the received signal throughout the circuit, the difference between the actual intensity of the progressively increasing wave lengths being progressively boosted by an increment which will give the intensity constant above described.

The proportion of the reinforcing currents seeping through the filter coil 31 must have an additive effect upon the received signal when reaching the input of the tube A, and in order to create this effect it will be appreciated that it is necessary that the proper phase connections be maintained between the terminals of the primary and secondary transformer coils 9-12 and the respective elements of the tubes A and B to which they are connected. In Fig. 1^a I have illustrated the proper way to make these connections.

For instance, these two coils 9 and 12 are wound in the same direction of rotation and connected to the tube elements so that the plate 8 of tube A is joined to the terminal P at the end of the primary adjacent the secondary winding. The grid 13 of tube B is connected to the terminal G of the secondary winding farthest from the primary winding. In Fig. 1^a these connections are indicated by the letters B, P, standing for battery and plate, and F and G indicating the filament and grid respectively.

In Fig. 2 I have shown diagrammatically a commercial form of radio receiving circuit embodying the principles above outlined. This layout comprises the radio frequency amplifying tubes A' and B' and the detector C' embodying grids 4^a, 13^a and 20^a; the filaments 6^a, 14^a and 21^a, and the plates 8^a, 16^a and 24^a. The antenna 1^a has the tuned primary coil 2^a associated with the secondary coil 3^a which is tuned to the frequency of the desired incoming signal by the variable condenser 7^a and is connected to the grid 4^a. The tubes A' and B' are coupled by means of a transformer, the primary 9^a of which is connected to the plate 8^a and the secondary 12^a connected to the grid 13^a, being tuned by the variable condenser 15^a. A similar transformer connects tubes B' and C' by having its primary winding 17^a connected to the plate 16^a and its secondary 19^a to grid 20^a and tuned by the variable condenser 22^a.

The several filaments 6^a, 14^a and 21^a are lighted from a six volt battery 50 by connecting their positive sides by a conductor 51 and their negative sides by a conductor 52, which conductors are connected respectively to the positive and negative terminals of said battery; a filament lighting circuit includes a rheostat 52^a by means of which the filament temperature may be controlled.

10 The input circuit of tube A' is completed by the conductor 500 which is joined to the battery lead 52 of filament 6^a, preferably at a point between the battery 50 and the rheostat 52^a, making the connection at the point shown has the advantage of giving a slight negative bias on the grid circuit due to the slight drop in voltage in said rheostat. In the conductor 500, I locate the resistance 33^a.

15 The output circuits of the radio frequency amplifying tubes A' and B' are completed through the usual 90 volt plate circuit battery 53, by connecting the negative pole of this battery to the common positive filament lead 51 and its positive pole to a conductor 55 leading to the end of the primary coil 9^a of the first coupling transformer and by a branch 56 leading to the corresponding coil 17^a of the second coupling transformer. The battery 53 is divided into a 22½ volt section 30 54, and the detector tube C' has its plate 24^a connected through the signal receiving device 23^a by the conductor 57 to the 22½ volt point of the plate circuit battery. Across this circuit is a by-pass condenser 58.

35 In this circuit arrangement I utilize the filtering elements before described, comprising a series inductance and shunt condensers at opposite sides thereof, which provide an effective path for the transfer of a portion 40 of the amplified long wave energy emitted from the output of the second tube B' to the input of the first tube A' via the use of a condenser of large capacity, such as a one microfarad condenser, 59. This condenser 45 is not shown in Fig. 1 because in the circuits therein illustrated a separate source of battery, or independent source of energy, is employed for each tube. However, in commercial receiving sets in which a common 50 so called "B" battery is employed, it becomes necessary to provide a means in the reinforcement conductor leading from one tube to the preceding tube to keep the high potential plate current of said first tube out 55 of the grid circuit of said preceding tube.

In the conductor 56 I interpose the radio frequency coil 31^a and the high resistance 32^a. Of the two condensers of the filter system that which is of the higher capacity indicated by 34^a, connects the conductor 56 with the wire 52, thus affording a path for high frequency currents to the filament 14^a at a point in front of the filter coil 31^a. The second condenser 35^a of the combination is connected in bridge between the

input or grid circuit conductor 500 and the filament lead 52 in which position it is located with reference to the condenser 34^a at the opposite side of the filter coil 31^a.

70 The values given for the condensers and coil of the filter system are the same as those mentioned in the description of the circuit of Fig. 1 and their operation is the same. It is understood that any tendency for current on the lowest wave length to escape from the output of tube B' into the input of tube A' is substantially blocked by the filter coil 31^a, being initially passed back to filament 14^a through the condenser 34^a. Should a portion of the current at this wave length pass through the coil 31^a, it will find a path to the filament 14^a through condensers 59 and 35^a. When the apparatus is operating on the longer waves, these finding a more difficult path through condenser 34^a and a more ready path through the filter coil 31^a pass with virtual freedom through the condenser 59 into the input circuit of tube A' and due to the high reactance of condenser 35^a at this wave length and high resistance 33^a are directed to and become a potential on the grid 4^a which being in step with the received signal, as determined by the phase connections of the transformer 9^a—12^a, reinforces said signal current to a point where the grid control of the electronic stream flowing from the filament 6^a to the plate 8^a becomes very effective.

90 The adaptability of my invention to various types of radio receiving systems is further illustrated in Fig. 3 in which I have shown an inverse duplex hookup of the general character shown in Patents No. 1,517,057 and 1,517,058 granted to me November 25th, 1924. The vacuum tubes G, H and I shown in this illustration represent in the order given the first and second stages of radio frequency amplification and the detector. The circuit connections as will be described are such that in the tube H the first stage of audio amplification is obtained and in tube G the second stage of audio amplification occurs.

100 60 indicates the antenna circuit having the tuned primary coil 61 with which is associated the secondary coil 61^a connected to the grid g and the filament g', these wiring connections including the variable condenser 62, by means of which the input circuit of tube G is tuned to the wave length of the desired incoming signal received from the antenna circuit.

110 The output of tube G comprises the plate element g², the circuit from which comprises the primary winding of a radio frequency transformer 65 one end of which is connected by conductor 66 to the positive terminal of the plate battery 67, the other pole of which is connected to the filament lead 75. The circuit is coupled to the input of tube H by con-

necting the secondary coil of the transformer to the grid h and coupled there-across is a tuning condenser 68. The plate circuit of this tube leads from plate h^2 through the primary winding of a second radio transformer 69 to battery 67 over conductor 70.

The detector tube I has an input circuit embracing the secondary coil of the last mentioned transformer, the ends of which are connected to grid i and filament i' and to the variable condenser 71. The output of this circuit leading from the plate i^2 is represented by the conductor 72 which extends to an intermediate point on the battery 67.

15 The filaments of the several tubes are lighted from the common battery 63 by connecting one end of each to the negative lead 64 and their other extremities to a common return 75. In one of these leads I include an ad-
20 justable resistance element 64^a for controlling their temperature.

Extending between the input circuits of the tubes G and H and the negative ends of their filaments are circuit connections con-
25 taining by-pass condensers 135 and h^3 , re-
spectively, and similar connections are made between the positive sides of the filaments of all the tubes and their respective output cir-
30 cuits which include similar condensers g^4 , 134
and i^4 . These several condensers are all of small capacity and arranged to pass high frequency current and impede the passing of audio frequency currents.

The circuit shown in Fig. 3 is of the in-
35 verse duplex type, hence the output of audio frequency currents from the detector tube I are fed into the input of tube H, and upon being amplified therein are passed into tube G for final amplification and delivered into
40 the signal receiving device which may be a telephone or loud speaker 77. To this end the coupling between the output circuit of tube I and the input of tube H is effected through an audio transformer 78, having an iron core,
45 by connecting its primary winding in the con-
ductor 72 and its secondary in the conductor 79, one end of which leads to the grid h of tube H, its other extremity being connected to one pole of a third, or separate battery 80,
50 the other pole of which is connected to the negative filament lead 64. A similar connec-
tion 81 leads from the circuit of grid g of tube G to the separate battery 80.

In place of another audio transformer for
55 effecting the audio connections between the output of tube H and the input of tube G, I utilize the elements of the filter combination before described in the following manner.

In the conductor 70 I place the radio fre-
60 quency filter coil 131 (corresponding to coil 31 of Fig. 1 and 31^a of Fig. 2). Between this coil and its point of connection to the battery 67 I place the high resistance 132. The higher capacity condenser of the pair of condensers
65 associated in action with said coil, indicated

by 134 is connected in a bridge extending be-
tween the conductor 70 and the filament h' . The other condenser of this pair is located in the bridge between the conductor 81 and fila-
70 ment g' , as indicated at 135.

A path for both radio and audio frequency currents is provided between the last stage of amplification and the input of the first tube by placing a large capacity condenser 159 which is connected at one of its sides at a point beyond the output end of coil 131 and at its other side is connected to conductor 81. This condenser 159 is placed in the position shown merely to prevent the high plate cur-
75 rent potential of battery 67 (present in con-
ductor 70) from reaching grid g of tube G.

Inserted in the conductor 81 between the condenser 159 and the battery 80 is the high resistance element 133 of the filter combina-
80 tion.

The operation of the foregoing circuit will be obvious. To state it briefly with respect to the features of my present invention it will be assumed first that a short wave fre-
90 quency is being considered. The high fre-
quency oscillations pass readily through the fixed condenser 134 to filament h' while at the same time the same oscillations, being of high frequency, encounter considerable difficulty in attempting to pass through the 95 filter coil 131 which has a real choking action at these frequencies. Such small amount of this current as may seep through this coil is readily passed to filament g' through the fixed condenser 135 and are thus prevented 100 from reaching the grid g of the first radio tube as a reinforcing action at this wave length is not desired.

As the larger wave lengths are tuned in on the amplifier the lower frequencies, corre-
105 sponding to these longer waves, find increasing difficulty in returning to filament h' through condenser 134 and at the same time pass more readily through the filter coil 131, the choking effect of which becomes less pro-
110 nounced the lower the frequency. Thus, an appreciable amount of the long wave oscillations pass back through the choke 131 to the grid g of the first radio frequency tube G reinforcing the original long wave signal to 115 such an extent as to compensate for the decreased coupling efficiency of the tuned trans-
former 65. The fixed condenser 135 which passed the high frequency seepage currents through filter coil 131 to filament g' offers 120 considerable impedance to the low frequency oscillations which have passed through for reinforcing purposes.

What I claim is:—

1. A high frequency signal system comprising a plurality of coupled audion circuits and a fixed feed-back circuit from the output of one audion circuit to the input of the preceding audion circuit, said feed-back circuit affording an easier path for low radio 125

frequency currents than for high radio frequency currents to substantially equalize the transfer of energy over a band of wave lengths.

5. 2. A wave amplifying system comprising a plurality of coupled amplifier circuits, a feed-back circuit from the output of one amplifier to the input of a preceding amplifier, and a wave filter in said feed-back circuit, said filter being designed to compensate for the discrimination in amplification of waves over a band of wave lengths.

3. In a wave amplifying system, a plurality of coupled amplifiers including at least one space discharge device and parallel paths for the transmission of energy between two of said amplifiers, one of said paths having electrical characteristics which introduce variations in the efficiency of transmission for different frequencies over a given range, said other path comprising means for compensating for such variation in transmission efficiency to produce substantially uniform transmission over the entire range and one of said paths providing energy transfer across and externally of a space discharge device.

4. In a wave amplifying system, a plurality of coupled amplifiers and parallel paths for the transmission of energy between any two of said amplifiers, one of said paths having electrical characteristics which introduce variations in the efficiency of transmission for different frequencies over a given range, and said other path comprising means for compensating for such variation in transmission efficiency to produce uniform transmission over the entire range, said paths being designed to transmit energy in opposite directions between said two amplifiers.

45. 5. A wave amplifying system comprising a plurality of coupled audion amplifier circuits, a feed-back circuit from the output of one amplifier to the input of a preceding amplifier, and a wave filter in said feed-back circuit comprising a series inductance and shunt condensers connected across said circuit on each side of said inductance.

50. 6. In an audion amplifier having tuning means for selective amplification of currents of varying frequency, a fixed feed-back circuit including a wave filter, conductively connected to the input and output circuits of the amplifier, to substantially equalize the transfer of energy and the sharpness of tuning over a band of wave lengths.

DAVID GRIMES.
